UNITED STATES PATENT OFFICE.

JAMES B. JENSON, OF SALT LAKE CITY, UTAH.

EXTRACTING APPARATUS.

1,388,718.

Specification of Letters Patent. Patented Aug. 23, 1921.

Application filed June 8, 1918. Serial No. 238,966.

To all whom it may concern:

Be it known that I, JAMES B. JENSON, a citizen of the United States, and a resident of Salt Lake City, in the county of Salt Lake and State of Utah, have invented a new and Improved Extracting Apparatus, of which the following is a full, clear, and exact description.

My invention relates to an eduction furnace or apparatus for extracting volatile and liquid substances from solids and more particularly oil from oil shale and sand, or the like. An object of the invention is to provide a simple and inexpensive apparatus whereby the recovery can be accomplished in an efficient manner.

Another object of the invention is to provide an apparatus whereby fractional recovery may be accomplished. A still further object of the invention is to provide an apparatus formed in sections or independent units connected in series so that the size and capacity of the apparatus can be easily varied by increasing or decreasing the number of units.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views:

Figure 1 is a vertical, longitudinal section through an apparatus embodying my invention;

Fig. 2 is an end elevation; and

Fig. 3 is a cross section on line 3—3, Fig. 1.

Referring to the drawings, 5—5 are the housings of the units which are in the shape of an elongated cylinder of suitable material so that heat can be applied to the same.

Each housing is provided with an inlet head 6 at one end and an outlet head 7 at the opposite end. These housings are disposed one above the other with their axes substantially parallel. The outlet head of the preceding unit is in communication with the inlet head of the succeeding unit, therefore,

the alternate units of the apparatus are disposed in a like manner. The inlet head of the first unit is connected to a suitable conduit 8 through which the material to be treated is fed. The outlet head of the last

unit is also connected to a conduit 9 through which the material treated is discharged. Each of the units has a plurality of spaced steam inlets 10 which are preferably located in the bottom part of the housing so that steam can be supplied to each of the housings through a suitable conduit 11.

The purpose of using steam and discharging the same under pressure in the bottom part of each housing or conduit is to obtain partial disintegration of the material to be retorted, and requires a complete emulsion of the material in steam, kept under pressure, that it may reach all particles, agitation or movement of particles, either continuously or intermittently as the particular material may require, to expedite extraction, to produce chemical action on the material and to prevent in part destructive distillation, to give uniformity in temperature throughout the mass, and as a preventative for the formation of dry dust and dangerously explosive gases during operation.

Each of the housings is provided with a conveyer 12 the bearings for which are provided in the inlet and outlet heads of the housing. Suitable stuffing boxes 13 are provided in the heads to prevent leakage along the bearings of the conveyer. The bearings are so formed that the conveyers have a clearance from the top of the housings, so that a gas chamber can be easily formed within the housing. Each of the chambers has an outlet conduit 14 which are connected to a condenser 15 where the volatilizing substance is collected.

The outlet heads 7 of each housing are restricted in cross section and the conveyers are concentric therewith and eccentric with the housings. The conveyers terminate at the heads so that their ends are a distance from the discharge openings of said heads so that the movement of the material by the conveyer of the housing is resisted at the outlet heads so that the communication between the two adjacent units is normally packed and the gases generated in the succeeding unit are prevented from passing into the preceding unit by the material packed in the communicating passage by the conveyer.

The outlet heads 7 serve as constrictors for the purpose of massing the material and filling the entire housing or cylinder with the crushed material for the purpose of preventing gases from passing from one cyl-

der to the other and the hotter gases rising to the upper cylinder which is to be kept the coolest. It consists of a casting or obstruction of smaller diameter than the regular cylinder extended from the discharge end of the conveyer to compel the latter to force the material onward by pressure. This results in the wadding or packing up of the material within the outlet heads beyond the conveyer ends and if it is desired to draw the gases from each cylinder separately, then the constrictor is placed at the discharge end of each cylinder. If gas is to be drawn from a group of cylinders, then a constrictor is placed between such groups of cylinders. In the eduction of oil from shale or sand, the constrictor is placed between such groups of cylinders as are intended to produce the different grades of oil and during the heating process, the tortuous formation of flues produced by the brick-work 16 gives a counterflow as distinction from the direction of movement of the material during treatment.

25 The heat may be supplied to the material within the housings interiorly or exteriorly. As shown the superimposing units are mounted in a suitable brick work 16 which is provided with a furnace 17 and a smoke-stack 18. The heat in this case is, therefore, supplied exteriorly. Material entering the first housing is fed toward the outlet end by the rotation of its conveyer. Steam is injected into the housing which comes in contact with the mass fed and stirred by the conveyer and facilitates the agitation of the material. The heat supplied to the housing facilitates the separation of the volatile matter from the mass which is digested by the steam. The material passing from the first cylinder to the second passes through the same cycle, and in view of the fact that the inlet end of the first cylinder is in proximity to the outlet end of the second cylinder the material is advanced by the conveyer in a direction opposite, or, in other words, the conveyer in the second housing revolves in an opposite direction, all of the conveyers being actuated from a suitable transmission mechanism.

50 Where fractional distillation is desirable, each of the housings will have its conduit 14 connected to a separate condenser. If desired, each of the housings may be inclined slightly toward its outlet end to facilitate the movement of the material in the housing.

When the material reaches the outlet head of the last housing, most of its volatile material has been extracted. By providing stuffing boxes in the heads, the recovery of the volatile matter may be carried out under high pressure, which pressure could be that supplied by the steam used for facilitating

the recovery of the volatile matter from the 65 solids fed through the apparatus.

One of the important features of this apparatus is the fact that I take the material in at a point of low temperature and bring it up to higher temperature by stages thereby 70 creating an eduction of the lighter oils such as benzin, toluol, gasolene, etc., without destruction of the molecules and it is to obtain this feature as well as that of handling by gravity that the apparatus is constructed 75 as it is, as well, also, as utilizing every particle of heat by absorption as it rises from one cylinder to another. These are features which are not obtained by any other apparatus and which make it possible 80 for me to get a complete extraction of oils from oil shale in from one and one-half to two hours that requires as much as twenty hours by other apparatus.

I claim:

1. In an extracting apparatus of the class described, a plurality of superimposed units each comprising an elongated cylindrical housing disposed with its axis in a substantially horizontal position, an inlet head at 90 one end of each of the housings, an outlet head at the other end of each housing, said outlet heads being of restricted cross section, the adjacent units having their inlet and outlet heads in communication, a screw conveyer revolvably mounted in each of said units to feed the material from the inlet toward the outlet heads, each conveyer having its end a distance from the discharge of the outlet head each of said housings having 100 spaced inlets for steam and an outlet for vapor, and means for supplying heat to said housings.

2. In an extracting apparatus of the class described, a plurality of superimposed units 105 each comprising an elongated cylindrical housing disposed with its axis in a substantially horizontal position, an inlet head at one end of each of the housings, an outlet head at the other end of each housing, said 110 outlet heads being of restricted cross section and disposed so as to be eccentric with the housing, the adjacent units having their inlet and outlet heads in communication, a screw conveyer revolvably mounted in each of said 115 units so as to be eccentric with the housing and concentric with the outlet head whereby a clearance is formed between the conveyer and the upper side of the unit, the conveyer having its end a distance from the discharge 120 of the outlet head each of said housings having spaced inlets for steam in the lower part of the housing and an inlet for vapor in the upper part of the housing, and means for supplying heat to said housings.

3. An extracting apparatus of the class described, comprising a furnace, a plurality of horizontal cylinders mounted in the

furnace, one above the other, each cylinder being provided with an inlet and outlet head outside of the furnace, the outlet heads being of restricted cross section, the adjacent 5 cylinders having their inlet and outlet heads in communication, a vertical conduit for feeding the material to one end of the uppermost cylinder, a revoluble screw mounted eccentrically in each cylinder to form a gas 10 chamber in the upper part of the cylinder, the screw having its blades terminating a distance from the discharge of the outlet head, a condenser, a pipe leading from the top of each cylinder and connected with the 15 condenser, and steam inlets opening into the lower portion of each of the cylinders.

4. In an extracting apparatus of the class described, a plurality of superimposed units, each comprising an elongated housing disposed with its axis in a substantially horizontal position, an inlet head at one end of each of the housings, an outlet head at the other end of each housing, certain of said outlet heads being of restricted cross section, 20 a feeding means mounted in each of said units to feed the material from the inlet toward the outlet heads and terminating at a spaced distance from the discharged openings of said outlet heads.

5. In an extracting apparatus or eduction 25 furnace for oil shale and the like, a plurality of superimposed units each comprising an elongated housing disposed with its axis in a substantially horizontal plane, the outlet 30 of one housing discharging into the inlet of the housing therebeneath, feeding means revolubly mounted in each of said units to feed the material from the inlet toward the outlet, certain of said feeding means terminating at a spaced distance from the dis-

charge ends of said housings or units, as and for the purposes specified.

6. In an extracting apparatus of the class described, a plurality of interconnected superimposed units, each unit being in the 45 shape of an elongated completely closed cylinder, means for supplying heat to said units, a revolving conveyer in each of the units mounted eccentrically therein at the bottom so that a clearance space is formed between 50 the conveyer and the upper side of the unit, and means to cause obstruction of the passage of material at the discharge end of each unit.

7. In an extracting apparatus of the class 55 described, a plurality of interconnected superimposed units, each unit being in the shape of an elongated cylinder open at the ends thereof and closed throughout its lateral wall, means for supplying steam under 60 pressure directly to the material therein, means for supplying heat externally to said units, feeding means mounted in each unit or cylinder, and means at the discharge end of each unit or cylinder to cause the material 65 to wad or pack therein, in a manner and substantially for the purposes specified.

8. In an extracting apparatus of the class described, an elongated cylindrical housing, 70 an inlet head at one end, an outlet head at the other end having a discharge pipe, said outlet head being of restricted cross section and eccentric with the housing and a screw 75 conveyer revolubly mounted in the housing so that the same is concentric with the outlet head and eccentric with the housing, said conveyer terminating at said outlet head spaced from said discharge pipe.

JAMES B. JENSON.
